Lighting Corporation, Seattle, Wash., a cor-
poration

Application May 29, 1931, Serial No. 541,040

3 Claims. (Cl. 176—126)

The present invention relates to luminous tubes of the type generally referred to as "spectral discharge" or "ionic discharge" tubes. By our invention, we provide a luminous ionic discharge tube and a system of operation therefor in which electrical energy is supplied to the luminous gases by means of a large area conductor separated from the gas by a wall of dielectric material. By the use of such an electrode, any gas which is 5 stable under the action of an electrical discharge may be used as the illuminant, including the so-called "active gases", because there is no contact between the gases and the conductor. Preferably the gas which we use may be entirely or in part 10 carbon dioxide, since such a gas, when ionized, gives a light approximating daylight, but it is to be understood that any other stable gas may be used.

We have found that, in order to pass through 20 the gas in the tube sufficient current to give a steady and brilliant light, the electrode area must be very large as compared with the cross-sectional area of the luminous tube if a source of supply with the ordinary commercial frequencies is to be used.

Electrostatic capacity electrodes for ionic discharge tubes as they have been suggested in the prior art, have been termed "conducting caps" with the caps covering as much as 40% of the tube 30 length in extreme cases. Using the same terminology to refer to the tube lighting system herein disclosed, the "conducting caps" would have to cover approximately 90% of the length of the tube in order to obtain a steady and brilliant 35 light, such as is desirable, and obviously such a length of tube devoted to the electrode would be undesirable.

It is one of the features of our invention to provide such an electrode as will have sufficient 40 area to give the desired illumination and, at the same time, have it compact enough so as not to occupy an undue amount of space.

We have also found that in such a tube with such large electrodes, the use of the ordinary 45 transformer by which the voltage of a current supply of commercial frequencies is stepped up to the necessary potential is highly undesirable, if not impossible, because of the resulting unsteadiness or flickering of the light and because of surges 50 in the circuit which may result in puncturing of the tube and destruction of the insulation on the transformer. We have found that these difficulties in the arrangement described are caused by the electromotive force applied to the tube be- 55 ing out of phase with the current therein, and

that this may be overcome by associating inductance with the external circuit, preferably in an amount sufficient to cause the current through the tube and the electromotive force to be substantially in phase. In this way, the effect of the 5 large electrostatic capacity, due to the large area electrodes, is substantially neutralized.

While the necessary inductance may be provided independently of the transformer, we have found it convenient to utilize the transformer 10 itself for this purpose. In order to accomplish this, we have found that a transformer having the proper amount of magnetic leakage can be used.

We have also found that good results may be 15 obtained when the current in the tube and the electromotive force are not exactly in phase, but, in such case, it is desirable to protect the windings of the transformer against puncturing which we have found to occur, under such circumstances, 20 in the outside windings of the secondary of the transformer. To prevent such puncturing, we preferably provide a transformer in which these outside windings are more heavily insulated than the remainder of the windings.

Preferably we obtain the large surface area 25 electrode by means of a plurality of small diameter tubes, each connected to the luminous tube, so that the interior of each small tube will be in 30 communication with the interior of the luminous tube. By using small diameter tubes for the electrode portion, we are able to make the walls thereof thinner than the walls of the luminous tube, with a corresponding increase in the electrostatic 35 capacity. Furthermore, by associating these small tubes in parallel groups, as we prefer to do, we are able to support each tube by the adjacent 40 tubes by providing a material to bridge over the spaces therebetween. The net result of our preferred arrangement is a compact group of small tubes, each of which, while thin and fragile and connected at one end only to the luminous tube, may nevertheless be supported in such a manner 45 that a considerable strength to resist breakage is provided.

Our invention will be best understood from the following description of illustrative embodiments of our invention.

In the drawings:—

Figure 1 is a diagrammatic view showing the 50 preferred form of luminous or ionic discharge tube and associated electrical circuit arrangement.

Figure 2 is an enlarged view, partly in side elevation and partly in longitudinal section, of one 55 of the electrodes.

Figure 3 is an enlarged fragmentary transverse section on the line 3—3 of Figure 2.

Figure 4 is an enlarged fragmentary section on the line 4—4 of Figure 2.

5 Figure 5 is a view part in section and part in elevation of the electrode and showing a further method of operating the electrodes.

Figure 6 is a view of a type of the transformer that may be employed.

10 Figure 7 is a section on the line 7—7 of Figure 6.

Figure 8 is a purely diagrammatic view illustrating the method of winding for the secondary coils of the transformer.

Figure 9 shows a modified form of electrode.

15 Figures 10 and 11 are enlarged fragmentary views on the respective lines in Figure 9 showing detailed features of construction.

20 Referring to the drawings in detail, and where-in similar reference characters designate corresponding parts thruout the several views, and referring particularly to the form of invention disclosed in Figures 1 to 8 inclusive, the letter A designates the luminous tube provided at its ends with the electrodes B. The tube A is preferably 25 formed of glass and may be of any desired form and size desired in accordance with the type of illumination desired for the luminous portion of the tube.

25 The electrodes B are shown connected in circuit with a transformer C of special construction which is for connection with a supply of low frequency low voltage alternating current, say of sixty cycle such as ordinarily supplied for commercial use.

30 Referring now to the specific construction of the large area capacity electrode B, which we have chosen for purposes of illustration, the same is made of a dielectric material such as glass and in one practical size has an approximate dimension of eighteen inches in length and three inches 35 in diameter. The electrode comprises a bell cap 5 for connection to an end of the tube A. The lower side of the hollow bell cap 5 is closed by a flat disc 6 to the under side of which is sealed a large number of small tubes 7 having 40 walls much thinner than the walls of the tube A. These small tubes 7 are closed at their lower ends and have their upper ends in communication with the interior of the hollow bell cap 5 thru apertures 8 formed thru the disc 6. These 45 thin walled tubes 7 are of equal length and formed of a suitable di-electric material such as glass. By way of example, there may be about one hundred and fifty of these thin walled tubes 7 of about 3 mm. diameter connected in slightly 50 spaced-apart relation to each other. This compact "bundling" of the small tubes 7 provides a very large area electrode as to external surface area compared with the volume of the electrode 55 as a whole.

60 While various forms of the so-called active gases may be employed, we prefer to use carbon dioxide, but it is to be distinctly understood that any gases which are stable under the action of electrical discharge may be employed. As will be observed, the interior of the electrode tubes 7 are in communication with the interior of the tube A and that the electrode tubes form terminals of the container for the gas to be ionized.

65 70 In the specific form illustrated, the plurality of small electrode tubes 7 are sealed within a capsule-like container or casing 10, preferably formed of a non-conducting material, such as glass, and, in the example shown, it is of tubular 75 formation and is closed at its lower end. This

casing 10 is sealed at its upper end to the hollow bell cap 5 and has an internal diameter slightly greater than the diameter of the group of electrode tubes 7 whereby the outermost annular series of the tubes are spaced slightly from the inner wall of the casing 10. The upper extremity of the casing is provided with an outwardly-pressed annular bead 11 providing an annular internal pocket about the upper extremity of the tubes 7. The lower end of the casing extends 10 slightly below the closed ends of the tubes 7 to provide a small chamber for a purpose to be subsequently explained.

The container or casing 10 may be completely 15 filled with a plastic mass of conducting material 12 forming a conductor for transfer of electrical energy to the gas to be ionized. By way of example, the mass may be agar mixed with salt water, this material being sufficiently "stiff" under the temperatures developed in the electrode 20 to provide desired support for the tubes 7. In the form shown in Fig. 3 this plastic conductor 12 completely fills the casing 10 and entirely encircles each of the small electrode tubes 7. In the form shown in Figure 5, the casing 10 is only 25 partially filled with the plastic conducting material 12 so as to form a support for the lower ends of the small electrode tubes 7, the remaining major portion of the casing being filled with either a luminous or non-luminous gaseous conductor such as neon or a liquid conductor such as water, if so desired. The pressure of the gaseous conductor used in the casing is not material. While it is preferred that the casing shall contain a sufficient quantity of the plastic conducting 30 material to form a support for the electrode tubes 7, such material may be omitted and the casing 35 may be filled completely with a gaseous or a liquid conductor.

40 For the purpose of filling the casing 10 with either a solid, liquid or gaseous conductor, it is provided at its upper end upon the bead 11 with a tip 13 and at its lower end with a tip 14. In the manufacture of the electrode, the tips 13 and 14 are open, permitting the conducting material 45 to be inserted through the tip 13 and the air in the casing to be expelled through the tip 14. After the casing is completely filled with the conducting material, the tip 14 is sealed off and the tip 13 may be also sealed off, as by heating. extending from the respective secondaries to the respective electrodes B.

As we have already said, we have found that, if the transformer C is of the usual type, the light resulting from such an arrangement is unsteady, and that we have found that this difficulty can be overcome by associating inductance with the circuit.

In the arrangement illustrated, this inductance is provided by variable magnetic shunts produced by a series of soft iron plates 24 between the primary and the secondary windings, these plates being designed to give to the transformer the desired inductance to neutralize, or partially neutralize, the electrical effect of the large capacity electrodes.

In order to minimize the possibility of a potential breakdown in the circuit, we preferably insulate the outer turns of each secondary winding to a greater extent than the remainder of the windings of the secondary, as diagrammatically illustrated in Fig. 8. This greater insulation may be provided by spacing the outer windings a greater distance apart than the inner windings of the coil, by providing a heavier coating of insulation on the wire of these outer windings and by sheets of insulating material, as at 19', or by any one or more of these methods.

Referring now to the form of capacity or condenser electrode shown in Figures 9, 10 and 11 the casing 10 shown in Figures 2 and 5 is dispensed with and the grouped series of small electrode tubes 1' are connected to and are in communication with a hollow bell cap 5' for connection with the ends of the light tube A as in Figure 1. The tubes 1' are coated with a metallic material 30, such as aluminum paint, carbon or graphite compositions, to provide a conducting coating upon the entire external surface of the tubes. After the metallic coating is applied, the tubes may be coated with one or more layers of lacquer or other suitable material to provide an insulating coating about and between the tubes to insulate the tubes against brush discharge and resultant production of ozone and consequent waste of energy. This coating of insulation also forms a binder for the tubes as shown in Figure 11 and reduces to a minimum the possibility of a tube being broken. Prior to application of the insulating coating 32, a terminal conductor 35 is electrically connected with the metallic coatings 30 at a point preferably midway the ends of the tubes 1'. This terminal 35 may consist of strands of wire suitably interwoven between the tubes 1' so as to contact with the metallic coating of each tube as shown in Figure 10. This interweaving of the wire 36 serves as a further reinforcement for the relatively small electrode tubes 1'.

It will be noted that the electrode shown in Figures 9, 10 and 11 does not differ to any great extent from the form shown in Figure 2 aside from the omission of the casing 10 permitting use of liquids, plastic and gaseous forms of conductors in connection with the bundled arrangement of small electrode tubes. In each form of electrode, the basic idea is retained; i. e., the provision of an electrode having a very large external surface area when compared with the overall dimensions of the electrode.

By our invention, the capacity of the condenser electrodes is not only increased much beyond the prior art practices, but the electrodes are also changed as to form and adaptability to various commercial uses.

When the electrode capacity is equivalent to that given by 10 to 15 feet of 25 mm. thin-walled glass tubing, electrical surges and flickering in the tube begin to be of importance and, as electrode capacities increase, it becomes essential to change the inductance of the circuit to an extent not heretofore known in the prior art of luminous tubes. When, however, sufficient inductance is provided, a luminous tube of satisfactory brilliance and steadiness is attained. For example, in tests with one of our lamps, with forty feet of light tube, 10 mm. in diameter, with an impressed voltage of 15,000 volts, and with the adjustment of inductance properly made, and each electrode having one hundred feet of 25 mm. tubing, approximately 350 milliamperes of current flows. Under these conditions, the intensity of illumination emitted by one foot of the light tube, at a distance of one foot, is sixteen foot candles using carbon dioxide as the luminous gas.

As a further illustrative example of the large area electrodes used, reference may be made to satisfactory results obtained by tests on a carbon dioxide luminous tube 34 feet long, a bore of 25 about 7 mm. and a gas pressure of 0.1 mm. When a current of about .245 amperes was applied through such a tube, illumination of about 12 c. p. per foot was obtained. Each of the electrodes used in this example was made up of 168 tubes of thin wall pyrex glass, each tube being 5 mm. in diameter and about 27 inches long, each electrode having an area of approximately 18,000 sq. cm. From this example, the large ratio between the area of our large capacity electrodes as compared with its volume will be evident.

It will be understood that, since nothing is in contact with the gas to be ionized except the glass walls, our tubes have an indefinitely long life.

Changes in the shape, size and arrangement of parts may be made to the form of invention herein shown and described, without departing from the spirit of the invention or the scope of the following claims.

We claim:

1. A luminous ionic discharge tube having a compact dielectric electrode for illuminating the gas in the tube, said electrode comprising a plurality of closely spaced small electrode tubes of dielectric material, each electrode tube being closed at one end and having its other end connected to the luminous tube, and a conducting material surrounding and contacting with the whole exterior of each of said electrode tubes, the material around any one tube being of a solid nature and being in contact with the material around adjacent tubes, whereby each tube is supported by adjacent tubes.

2. A luminous ionic discharge tube having a dielectric electrode for illuminating the gas in the tube, said electrode comprising a plurality of electrode tubes of dielectric material, each electrode tube being closed at one end and having its other end connected to the luminous tube, the electrode tubes being arranged in a group side by side, a container surrounding the group, a plastic conducting material in the container and covering at least the sealed ends of the tubes in the group to support the same, substantially the remainder of the container also being filled with conducting material.

3. A luminous ionic discharge tube having a dielectric electrode for illuminating the gas in

the tube, said electrode comprising a plurality of electrode tubes of dielectric material with the interior of each of the electrode tubes in communication with the interior of the luminous tube, conducting material contacting with the exterior of each electrode tube and a casing in

which said electrode tubes and conducting material are located, said conducting material being in contact with the inside surface of said casing and being supported thereby.
